UNITED STATES PATENT OFFICE

99,123

DESIGN FOR A DRESS

Mona Freed, New York, N. Y.

Application March 2, 1936, Serial No. 61,433

Term of patent 3½ years

To all whom it may concern:

Be it known that I, Mona Freed, a citizen of the United States of America, residing in Manhattan, county of New York, and State of New York, have invented a new, original, and ornamental Design for a Dress, of which the following is a specification, reference being had to the accompanying drawing, forming part thereof, wherein,

The vertical lines on the front waist and skirt portions of the dress represent tucks.

I claim:

The ornamental design for a dress, substantially as shown, and described.

MONA FREED.
